UNITED STATES PATENT OFFICE.

THEODORE L. RICHMOND, OF BUFFALO, NEW YORK, ASSIGNOR TO THE BUFFALO SCALE COMPANY, OF SAME PLACE.

RECORDING-SCALE.

SPECIFICATION forming part of Letters Patent No. 562,324, dated June 16, 1896.

Application filed August 24, 1895. Serial No. 560,413. (No model.)

To all whom it may concern:

Be it known that I, THEODORE L. RICHMOND, a citizen of the United States, residing at Buffalo, in the county of Erie and State of New York, have invented certain new and useful Improvements in Recording-Scales; and I do hereby declare the following to be a full, clear, and exact description of the invention, such as will enable others skilled in the art to which it appertains to make and use the same.

My invention relates to improvements in recording balance-scales; and it consists in certain novel features of construction, combinations, and arrangement of parts, as will be hereinafter described and claimed, whereby an improved recording-scale is produced.

In the accompanying drawings, forming part of this specification, Figure 1 represents a side elevation of a scale-beam with my invention applied thereto. Fig. 2 represents a bottom plan view of the same. Fig. 3 represents a side elevation taken on the side opposite from that shown in Fig. 1, the scale-beam being broken away. Fig. 4 represents a side elevation of the main poise with its side walls and the auxiliary beam removed. Fig. 5 represents a detail rear elevation of the front plate of said main poise. Fig. 6 represents a transverse vertical section through said main poise and auxiliary poise. Fig. 7 represents a detail side elevation of the auxiliary poise with its front plate removed. Fig. 8 represents a detail rear elevation of said front plate. Fig. 9 represents a detail rear elevation of said auxiliary poise, and Fig. 10 represents a plan view of the card I prefer to use with my invention after being stamped.

A in the drawings represents the main scale-beam; B, its adjustable poise; C, the auxiliary beam on said poise, and D the auxiliary poise on said latter beam.

The main scale-beam may be of the ordinary construction and provided along its under side with type *a*, arranged at intervals thereon, so as to correspond in position, and to the numerals, indicated with the divisions of the scale *a'*, arranged on the side of said beam. The top of the said main beam is provided with a longitudinal bead having

ratchet-teeth cut thereon so as to form a rack *a*². Horizontal supporting portions *a*³ and *a*⁴ are left on the respective sides of said bead and the portion *a*⁴ being provided with a wheel-guiding ridge *a*⁵, and the portion *a*³ serving for two of the wheels to run upon. The rear wall of the main poise passes up at the rear of the said main beam, and is provided at its top with a horizontal overhanging portion, and a detachable face-block *b*. Antifriction-rollers *b'* are journaled in suitable recesses in the upper end of said poise and said block, respectively. Each of the said rollers *b'* comprises two spaced wheels mounted on an axle, one having a flat tread to run upon the portion *a*³ of the beam and the other a V-grooved tread to run upon the ridge *a*⁵, and thus guide the poise against lateral movement. The spaces between the wheels are to permit the passage of said wheels along each side of the rack *a*². The block *b* is recessed longitudinally, near its bottom, so as to form a space *b*², which fits over the rack without engaging the same. A pawl *b*³ is pivoted in said block and projects below the same through the space *b*², so as to engage the rack *a*². This pawl also projects through the top of the block and is provided with an operating-handle *b*⁴. A toe *b*⁵ on said pawl is engaged by the end of a flat spring *b*⁶, mounted in the block *b*, so that said pawl is normally held in engagement with the rack *a*². An indicating-finger *b*⁷ is attached to said block *b* and extends down over the front of the beam, so as to travel over the scale as the poise is moved along and thus indicate to the eye the weight on said scale. The said block *b* is attached to the upper end of the poise by bolts or screws.

It will be seen from the foregoing that the main poise is supported by the antifriction-rollers that roll along the top of the main beam. The lower part of the said poise B projects forward under the beam and is hollow to accommodate the inking and printing mechanism. The upper wall of said hollow inwardly-projecting portion of the poise is provided with two end slots *f*, through which the inking-ribbon *F* passes as it is wound from one reel *f'* to the other reel *f'*. These reels *f*' *f* are

are mounted on the squared ends of arbors f^2 5, which pass through the rear wall of the poise. Each of these arbors is reduced where it passes through said rear wall, so as to form shoulders f^3 , which bear against the inner side of said rear wall, and the outer ends of said arbors are provided with operating-heads f^4 , under which the two free ends of a centrally-fixed spring f^5 bear, so as to cause sufficient 10 friction when said arbors are rotated to wind or unwind the ribbon taut all the time. The heads of said arbors are milled, so that they can be more readily rotated when the position of the ribbon is to be changed to bring an unused portion in line with the printing devices. 15 Just above the reels f^6 f^7 are arranged studs f^6 f^7 , over which the ribbon passes smoothly after passing through said slots. About midway between the slots f^6 f^7 is formed to permit an impression-plunger H to 20 pass upward and force a previously-inserted card or paper first against the ribbon and then force the ribbon against the type immediately above on the main beam, and thus print an impression of said type on said card. The upper end of the plunger H is faced with a cushion-block of some flexible material, preferably rubber, which is set in a groove h in said plunger. The said plunger is provided 25 at its lower end with a guiding-stem h' , that passes through an aperture in the bottom wall of the poise. The plunger is kept normally down by a flat spring h^2 , attached at one end to the bottom wall of the poise, and 30 having its other end bifurcated, so as to extend on opposite sides of the stem h' and rest upon a transverse stop-stud h^3 , mounted in said stem. The upper side of the top wall of the poise is provided with a slotted plate h^4 , 35 having card-guiding flanges h^5 , so that the card is guided to the proper position over the plunger. Said flanges h^5 also hold the ribbon F up at this point, so that the card will always pass under and never over it when being inserted. 40

A slide K is mounted in the front plate b^9 , and a stud h^3 of the plunger engages the wall of an aperture K' in the slide. The plunger is operated by a handle L , journaled in said 45 front plate and provided with an angular arm k' , which engages an offset or shoulder H' of the plunger. Slots b^{10} and k^3 are cut in the front plate and slide, respectively, whereby a card may be inserted through said front 50 plate and slide.

When the slide is in its normal position, the slots b^{10} and k^3 do not exactly coincide, and the top portion of the slot b^{10} is covered by said slide, so that the card must be inserted 55 at the bottom of said slot b^{10} , which insures the card passing under and not over the ribbon. As the slide is raised by depressing the handle L , the card is raised also by the plunger.

At each end of the main poise is mounted a forwardly-projecting arm c . The auxil-

iary beam C is attached at each end to said arms. The under side of this beam is provided, like the beam A , with spaced type c' for printing the amount in pounds. This 70 beam is for printing from ten pounds to a thousand pounds in groups of ten pounds, while the main beam is for printing from one thousand to one hundred and twenty thousand pounds in groups of one thousand, but 75 of course these proportions could be varied if so desired. The upper side of the auxiliary beam is provided with teeth forming a rack c^2 .

The auxiliary poise D is hollow and is provided with lateral passages d in its side wall, so that said poise surrounds and slides on the beam C . A V-shaped projection c^3 is mounted on the inner side of the top wall of said poise, so as to engage the rack c^2 and 85 hold the poise firmly in any position to which it is moved.

The auxiliary poise is provided with an inked ribbon F' and mountings F^2 , and a plunger d^2 , which parts are the same as those 90 in the main poise, except that the plate h^4 and the operating-handle L and arm k' are omitted, and the spring h^2 modified; a spring h^6 , having one end secured to the poise and the other end working in a slot in the plunger-stem, being substituted for the spring h^2 . The projecting lower end of the plunger-stem 95 in this case is provided with a knob h^7 , by means of which said plunger is operated.

The front plate for the auxiliary poise is 100 provided with an aperture h^8 , and an index-pointer h^9 , by means of which the scale on the beam can be seen and the weight indicated. Said front plate is also provided with a slot h^{10} , through which the record-card is 105 inserted. A slide j is mounted in a recess in the back of the front plate, and is provided with a card-introducing slot j' , which operates in conjunction with the slot in the front plate in a similar manner to the slide in the main 110 poise. The slide in this case is operated by a stud j^2 on the plunger d^2 , which enters a slot j^3 in said plate.

When a balance is reached in operating the scale, by moving the poises on their respective beams, a card is first inserted in one poise and stamped, and then in the other, thus making a permanent and accurate record of all amounts weighed. The invention is 120 applicable to all classes of scales, but is more especially intended for railroad-track scales, hopper or grain scales, and hay, wagon or platform scales. In Fig. 10 of the drawings I have shown a card marked or printed in the manner I prefer, it having the scale-indications from both the beams printed thereon.

An important feature of my scale-beam, over ordinary recording scale-beams, is the fact that the weightman can stamp upon cards or paper slips both the large and small 130 weights without moving from his position opposite the main poise. This he can do by

simply taking the card out of the large poise and inserting it at once into the small poise which is in immediate relation to the large poise, and is carried by it. With other scale-beams which record the large and small weights, the construction is such that it is necessary to stamp the large weights and then to go to a small beam on the back end of the large beam from which to get the unit-weights, thus rendering it necessary for the weightman to be constantly moving from one end of the beam to the other. I believe it is a new and important improvement, whether an inked ribbon is used or not, to have two recording-beams arranged relatively to one another in the manner I have shown and described; said main recording-beam and auxiliary recording-beam having, respectively, impression devices on their lower edges, and being properly graduated on their front sides; and said main beam and auxiliary or unit beam having means for forcing cards or slips of paper into contact with said impression devices, so as to take permanent records therefrom; this combination being very convenient and insuring accuracy, as it enables the weightman to mechanically record the small weights on the auxiliary beam without changing his position in respect to the main poise.

30 To illustrate: supposing, for instance, that there is a weight on the main beam of fifty-five thousand two hundred and ten pounds, the poise would be moved on the main beam out to "55,000," and the poise on the auxiliary or unit beam would be moved out to "210," and thereupon the card would first be inserted in the slot on the large poise, and stamped and withdrawn, then (without moving from his position to another part of the beam, or using 40 a printed slip) the same card inserted into the auxiliary poise and stamped; the card on being withdrawn showing fifty-five thousand two hundred and ten pounds. It is readily seen that this cannot be accomplished with recording scale-beams heretofore devised.

Having now described my invention, what I claim as new, and desire to secure by Letters Patent, is—

1. In a scale, the combination with a main scale-beam having printing-type arranged along its length, of a main poise adapted to travel on said beam, and provided with devices whereby a record may be taken from said type, an auxiliary scale-beam mounted 50 on said main poise and having printing-type arranged along its length, an auxiliary poise on said latter beam, having devices whereby a record may be taken from said latter type, substantially as described.
2. In a scale, the combination of a main scale-beam having stationary printing-type arranged along its under side, a poise constructed to travel on said beam and carrying an inked ribbon, and provided with means 60 for the introduction of a card below the ribbon, and a vertically-operated plunger mounted on and moving with said poise and constructed

to force the card and ribbon in contact with the printing-type on the scale-beam, an auxiliary scale-beam mounted on said poise and 70 provided with printing-type along its under side, an auxiliary poise mounted on said auxiliary beam and carrying an inked ribbon and provided with means for the introduction of a card below the ribbon and a vertically-operated plunger mounted on said auxiliary poise and moving therewith and constructed to force the card and ribbon in contact with the printing-type on the auxiliary scale-beam, substantially as described. 80

3. In a scale, the combination of a main scale-beam having stationary printing-type arranged along its under side, and a rack upon its upper side, a poise constructed to travel on said beam and carrying an inked ribbon and provided with means for the introduction of a card below the ribbon, a vertically-operated plunger mounted on and moving with the poise and constructed to force the card and ribbon in contact with the printing-type on the scale-beam, and a pawl on said poise for automatically engaging the rack on the scale-beam, an auxiliary scale-beam mounted on said poise and provided with printing-type along its under side, an auxiliary poise mounted on said auxiliary beam and carrying an inked ribbon and provided with means for the introduction of a card below the ribbon and a vertically-operated plunger mounted on and moving with said auxiliary poise and constructed to force the card and ribbon in contact with the printing-type on the auxiliary scale-beam, substantially as described. 90

4. In a scale, a poise constructed with an impression-plunger and provided with a slot through its face-plate, and with a sliding plate on the rear side of said face-plate, which slide has a slot through it for working in conjunction with the slot in the face-plate, and said slide constructed to be operated simultaneously with the plunger, whereby the proper introduction of a card to be stamped is insured, substantially as described. 105

5. In a recording-scale, a poise provided 115 with a chamber, arbors in said chamber provided with means for operating them from the outside, a vertically-reciprocated impression-plunger, guides for directing a ribbon above the impression-plunger beneath the 120 impression-type, a slotted plate provided with ribbon-supporting flanges which form a guide-way for the introduction of a card beneath the ribbon, substantially as described.

6. In a recording-scale, the combination 125 with a main scale-beam having impression-type arranged along its length, of a main poise adapted to travel on said beam, devices for taking a record from said type mounted on and traveling with said poise, an auxiliary 130 scale-beam mounted on said main poise and having impression-type arranged along its length, an auxiliary poise on said latter beam, devices mounted on and moving with the aux-

iliary poise whereby a record can be taken from said latter type, the main and auxiliary beam being in such relation and arrangement to each other that a weightman can take the 5 record from the main scale-beam and that from the auxiliary scale-beam without leaving his position, substantially as described.

In testimony whereof I hereunto affix my signature in presence of two witnesses.
